(57) **CLAIM**

We claim the ornamental design for a card removal tool, as shown and described.

DESCRIPTION

FIG. 1 is a front perspective view of a card removal tool in a first configuration;

FIG. 2 is a front elevational view of the card removal tool of FIG. 1;

FIG. 3 is a back elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a front perspective view of the card removal tool in a second configuration;

FIG. 9 is a front elevational view of the card removal tool of FIG. 8;

FIG. 10 is a back elevational view thereof;

FIG. 11 is a left elevational view thereof;

FIG. 12 is a right elevational view thereof;

FIG. 13 is a top plan view thereof;

FIG. 14 is a bottom plan view thereof;

FIG. 15 is a front perspective view of the card removal tool in a third configuration;

FIG. 16 is a front elevational view of the card removal tool of FIG. 15;

FIG. 17 is a back elevational view thereof;

FIG. 18 is a right elevational view thereof;

FIG. 19 is a left elevational view thereof;

FIG. 20 is a top plan view thereof; and,

FIG. 21 is a bottom plan view thereof.
